REFRIGERATING APPARATUS

Lawrence A. Philipp, Detroit, Mich., assignor, by
mesne assignments, to Nash-Kelvinator Corporation,
Detroit, Mich., a corporation of
Maryland

Application May 24, 1934, Serial No. 727,261

5 Claims. (Cl. 62—89)

My invention pertains to means for absorbing odors in refrigerators and more particularly to a method of and means for absorbing odors in household refrigerators.

5 The accumulation of odors in refrigerators is an annoyance well known to users of all kinds of refrigerators and ice boxes. The problem of eliminating this unsatisfactory condition has not been successfully solved because known odor absorbers were too large and expensive, or were 10 not efficient or conveniently replenishable.

It is accordingly an object of my invention to provide an odor absorbing means for refrigerators which has a small volumetric displacement and 15 presents a large odor absorbing surface.

It is a further object of my invention to provide odor absorbing means which is so arranged and disposed that it will more efficiently absorb the odors from the air as it circulates within the 20 refrigerator.

It is also an object of my invention to provide an efficient odor absorber which will occupy a small space within the refrigerator, and which may be conveniently replenished.

25 In accordance with my invention I provide a layer of some odor absorbing substance, such as white mineral oil, spread over a large surface under the cooling unit in the path of the cooled circulating air. In one embodiment of my invention a baffle plate is provided under the cooling unit to regulate the flow of air and a piece of oiled paper is spread on the upper surface of the baffle plate where it is exposed to the flow of cooled air as it passes down from the cooling 30 unit. The excess paper is provided in a small roll at the top of the baffle plate from which a new piece of paper is conveniently rolled out to expose a fresh surface. In this embodiment an oil container may be also provided for slowly 35 dripping oil onto the surface, thus continually producing a fresh odor absorbing surface.

In accordance with another embodiment of my invention white mineral oil is poured in the drip pan and floats on the water in the pan. As 40 the air circulates over the cooling unit the cooled air passes down over the drip pan and the odors in the air are readily absorbed in the oil surface. The oil is very conveniently removed when required.

45 The invention itself, however, both as to its organization and its method of operation, together with additional objects and advantages thereof, will best be understood from the following description of specific embodiments, when

read in conjunction with the accompanying drawing, in which:

Fig. 1 is a sectional view of the upper portion of a refrigerator provided with an odor absorber arranged in accordance with my invention; and

Fig. 2 is a sectional view showing a modification thereof.

Referring more specifically to Fig. 1 of the drawing I have shown a refrigerator cabinet 10 having side walls of usual heat insulating construction and a door 11. The cabinet encloses a cooling unit 12 supported at the top of the compartment in the usual manner. The flow of air in the compartment is directed over and under the cooling unit 12, by a baffle plate 13 which is 15 mounted thereunder.

Mounted on the upper end of the baffle plate adjacent to the door of the cabinet is a roll of paper 14 for conveniently supplying a strip of paper 15 which lays on the upper surface of the 20 baffle 13. The roll of paper may be supported on a roller 16 the ends of which may be journalled in slotted bearings in upturned ears 17 provided on opposite sides at the upper end of the baffle plate 15. The paper is coated with an odor absorbing substance such as white mineral oil.

As the air circulates in the compartment it passes up the rear wall of the cabinet 10 thence around the cooling unit 12, down the front of the cabinet and over the upper surface of the 30 baffle 13. In this manner the air is repeatedly exposed to the odor absorbing surface on the strip of paper 15 at a time in its cycle of circulation when its condition is most favorable for depositing the odors. When the paper 15 becomes 35 saturated with odors a new piece of paper may be very conveniently rolled out and a new odor absorbing surface exposed.

The odor absorbing surface may be continuously replenished from an oil containing vessel 40 or trough 18, which is mounted above the upper end of the strip of paper 15 on a suitable bracket and is provided with a wick 19 for continuously applying oil to the paper from the vessel.

In accordance with my invention a conventional refrigerator installation may be provided with an effective odor absorbing surface by adding a small quantity of odor absorbing substance 45 21, such as white mineral oil, in the drip pan 22, which is usually placed on a shelf 23 directly 50 under the cooling unit 12, as shown in Fig. 2. The oil 21 floats on any water 24 in the drip pan 22, and a very small quantity of oil is sufficient to provide an odor absorbing film of large area.

As the air in the cabinet 10 circulates contin-

55

uously and is cooled by the cooling unit 12 it passes down over the drip pan 22 where the odors are readily absorbed in the oil surface. In this arrangement only a small quantity of oil is used 5 and it is very conveniently replenished.

It will therefore be seen that I have provided an efficient odor absorber for refrigerators which is compact, efficient and conveniently replenishable.

10 Although I have shown and described certain specific embodiments of my invention, I am fully aware that many modifications thereof are possible. My invention, therefore, is not to be restricted except insofar as necessitated by the 15 prior art.

I claim as my invention:

1. In combination a heat insulating refrigerator cabinet, a cooling unit mounted in the upper portion of said cabinet, a strip of paper, a film 20 of oil thereon, and means for supporting the paper adjacent to the cooling unit in the path of the cooled circulating air.

2. In combination a heat insulating refrigerator cabinet, a cooling unit mounted in said cabinet, odor absorbing and baffle means comprising 25

a strip of paper, a film of oil thereon, and means for supporting said paper adjacent the cooling unit in the path of the circulating air.

3. In combination a refrigerator comprising a heat insulating cabinet and a cooler unit mounted in said cabinet, a baffle plate angularly disposed under said cooling unit, a roll of paper mounted adjacent one end of the baffle plate for supplying a strip of paper across the upper face of the baffle plate and an odor absorbing substance on said paper. 5

4. In combination, a heat insulating refrigerator cabinet, a cooling unit mounted in said cabinet, a baffle plate supported under said unit, a strip of paper on the upper surface of said baffle 10 plate, and an odor absorbing substance on said paper. 15

5. In combination, a heat insulating refrigerator cabinet, a cooling unit mounted in said cabinet, a strip of paper, means for continuously 20 applying a layer of odor absorbing substance thereon, and means for supporting said paper adjacent the cooling unit in the path of the circulating air.

LAWRENCE A. PHILIPP. 25
